UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

THREAD-CONTROLLING DEVICE FOR SEWING-MACHINES.

1,326,669.

Specification of Letters Patent. Patented Dec. 30, 1919.

Application filed May 15, 1919. Serial No. 297,306.

To all whom it may concern:

Be it known that I, JOHN KIEWICZ, a citizen of the United States, residing at Boston, county of Suffolk, State of Massachusetts, have invented an Improvement in Thread-Controlling Devices for Sewing-Machines, of which the following description, in connection with the accompanying drawing, is a specification, like characters 10 on the drawing representing like parts.

In some buttonhole sewing machines such, for instance, as illustrated in United States Patents No. 1,188,942, June 27, 1916, and No. 1,255,970, February 12, 1918, the under 15 thread mechanism is carried by a rotary turret which is provided with a throat-plate through which the under thread is delivered, and means are also provided for delivering a stay-cord or filling thread to the 20 buttonhole and laying it along the edge of the buttonhole as the stitching proceeds, so that the edge stitches on the buttonhole will be formed over the stay-cord.

Buttonhole sewing machines of the above- 25 mentioned type are usually constructed and organized so that when the machine is started the first operation is to clamp the work, after which the parts are moved to bring the work into stitching position, and 30 when the work is in stitching position, the stitch-forming mechanism is set in operation to form the edge stitches on the buttonhole. Sometimes the buttonhole is cut immediately after the work is clamped and before 35 the work is shifted into stitching position, and sometimes the buttonhole is cut after the stitching on the buttonhole has been completed. In either case the turret carrying the under thread mechanism is given a turn- 40 ing movement after one buttonhole has been completed and before the stitching on the next buttonhole begins, such turning movement operating to bring it into proper position for the beginning of the stitching on a 45 buttonhole, and during this turning movement, the stay-cord or filling thread is sometimes subjected to a backward pull, tending to draw it out of the throat-plate.

Some sewing machines of the above-men- 50 tioned type are provided with thread-cutting means which becomes operative after the completion of a buttonhole to cut the stay-cord close to the work, and in such a

manner as to leave a proper length of stay-cord at the throat plate to start the next 55 buttonhole.

It is, of course, important that at the beginning of the stitching on the buttonhole there should always be a sufficient length of stay-cord projecting from the throat-plate 60 so that the first stitches of the buttonhole well be formed over the stay-cord. It is also desirable that there should be no extra length of stay-cord projecting from the throat-plate because the presence of such extra 65 length not only is wasteful, but also produces a projecting end which requires to be trimmed after the buttonhole is completed. When the stay-cord is cut at the end of each stitching operation so as to leave just the 70 proper length projecting to start the next buttonhole, it sometimes happens that during the turning movement of the turret which occurs between buttonholes, the stay-cord is subjected to a backward pull which withdraws the cut end of the stay-cord from the 75 throat-plate slightly, thus leaving an insufficient end projecting therefrom to start the next buttonhole. When this occurs a defective buttonhole will be produced.

The object of my present invention is to provide a simple device for preventing any backward movement of the stay-cord while freely permitting its forward movement, so that it will be possible to cut the stay-cord 80 at the end of each buttonhole and leave just the right length projecting from the throat-plate to begin the next buttonhole without danger that this proper length will become 85 shortened due to a backward pull of the stay-cord, as above described.

With my invention, therefore, a proper length of stay-cord for beginning each buttonhole is always insured, and it is not necessary to provide any extra length which 90 causes more or less waste and necessitates a trimming of the cord after the buttonhole is completed.

In order to give an understanding of my invention, I have illustrated in the drawings 100 a selected embodiment thereof which will now be described, after which the novel features will be pointed out in the appended claims.

In the drawings, Figure 1 is a side view 105 of the turret of a buttonhole sewing machine

carrying the under thread mechanism and throat-plate and having my improvements applied thereto;

Fig. 2 is a top plan view;

5 Fig. 3 is an enlarged top plan view of the throat-plate showing my improved thread-clamping device;

Fig. 4 is a side view of Fig. 3.

Inasmuch as my invention relates simply 10 to the means for controlling the stay-cord, I have not deemed it necessary to illustrate herein a complete buttonhole sewing machine, but have shown in the drawings only the turret carrying the under thread mechanism 15 to which my improvement is applied.

1 indicates generally the turret which carries the under thread mechanism and which is mounted for rotation in a suitable bearing or frame situated beneath the bed 20 plate of the sewing machine, all as will be apparent from United States patents mentioned above No. 1,188,942 and No. 1,255,970.

The turret is provided with the throat-plate 2 having an aperture 9 through which 25 the upper and under needles pass and also carries the usual under needle that manipulates the under thread and the looper which cooperates with the upper needle and the under needle in forming the edge stitches 30 on the buttonhole. These parts are of the usual construction found in sewing machines of the type illustrated in said above-mentioned patents and are actuated by the vertical reciprocating movement of the spindle 35 3 which is situated axially of the turret.

The turret 1, it will be understood, has a rotative movement during the stitching around the eye of the buttonhole and also has a turning movement during the shifting 40 of the work from buttonhole-cutting to stitching position.

The throat-plate 2 has the usual stem 4 depending therefrom which is received in a groove 5 formed in the top of the turret, 45 said stem being retained in position by the clamping screw 6, this being the usual construction in machines of this type.

The throat-plate is provided with the aperture 7 through which the stay-cord 8 50 is led into the opening 9 formed in the throat-plate for the passage of the needles, said stay-cord being delivered through said opening 9 to the work. The turret is also provided with a guide opening 10 through 55 which the stay-cord extends.

The parts thus far described are or may be all as usual in sewing machines of this type.

My present improvements comprise a 60 novel thread-clamping means associated with the throat-plate and which operates on the thread adjacent the aperture 7 and is constructed so as to prevent backward movement of the stay-cord 8 while freely 65 permitting its forward movement. The

throat-plate is formed adjacent the aperture 7 with a laterally-extending clamping shoulder 12 so that the stay-cord passes over said shoulder 12 as it is led into the aperture 7. Extending from the stem 4 of 70 the throat-plate is an arm 13 to which is secured a clamping spring 14, the end 15 of which rests against the shoulder 12. This spring is shown as secured to the arm 13 by means of a screw 16, and said spring is 75 so shaped that the end 15 thereof stands at a slight angle to the shoulder. This spring is made so that its resiliency tends to hold the end 15 against the shoulder 12. The arm 13 is bent laterally at its end, as 80 shown at 17, and is provided with a guide-eye 18 through which the stay-cord passes, said guide-eye being so positioned that the stay-cord will be guided over the shoulder 12 on its passage to the aperture 7. 85

The construction of the spring 14 and its position relative to the shoulder 12 are such as to permit the stay-cord to be freely moved forwardly from the guide-eye 18 to the aperture 7, the tension on the cord tending to move the spring away from the shoulder 12. When the feeding movement of the cord 8 ceases, the resiliency of the spring 14 causes the end 15 thereof to grip the cord against the shoulder 12, and any 90 tendency to draw the cord backwardly will cause the end 15 of the spring 14 to lock the cord firmly against said shoulder. The spring 14, therefore, permits the cord 8 to be freely fed forwardly as required, but 100 operates to prevent any backward movement of the cord. Thus if during the turning movement of the turret preliminary to the beginning of the stitching operation on a buttonhole there is any tendency to draw the 105 cord 8 backwardly, such tendency will be resisted by the spring 14 and a proper length of cord will always be projecting through the opening 9 in the throat-plate to insure the proper operation at the beginning of the 110 stitching on a buttonhole.

I claim:

1. In a buttonhole sewing machine of the type having a rotary turret carrying the under thread mechanism, the combination 115 with a throat-plate carried by said turret and provided with an aperture through which the stay-cord is led to the work and also with a clamping shoulder adjacent said aperture, of a resilient clamping arm co-operating with said shoulder to prevent the stay-cord from backward movement.

2. In a buttonhole sewing machine of the type having a rotary turret carrying the under thread mechanism, the combination 125 with a throat-plate provided with an aperture through which the stay-cord is led to the work and also provided with a clamping shoulder adjacent said aperture, of a stem depending from said throat-plate and by 130

which it is secured to said turret, and a resilient clamping arm carried by said stem and coöperating with said shoulder to prevent the stay-cord from backward movement.

3. In a buttonhole sewing machine of the type having a rotary turret carrying the under thread mechanism, the combination with a throat-plate provided with an aperture through which the stay-cord is led to the work and also provided with a clamping shoulder adjacent said aperture, of a stem depending from said throat plate and by which it is secured to said turret, an arm extending laterally from said stem, and a resilient clamping member supported by said arm and coöperating with said shoulder to prevent the stay-cord from backward movement.

20 4. In a buttonhole sewing machine of the type having a rotary turret carrying the under thread mechanism, the combination with a throat-plate carried by said turret, said throat-plate having an opening through which the needles operate and also having both a laterally-extending aperture leading to said opening through which the stay-cord is delivered to the work and a clamping shoulder adjacent said aperture, of a resilient clamping member coöperating with said shoulder to prevent the stay-cord from backward movement.

25 5. In a buttonhole sewing machine of the type having a rotary turret carrying the under thread mechanism, the combination with

a throat-plate carried by said turret, said throat-plate having an aperture through which the stay-cord is led to the work and also having a fixed clamping shoulder adjacent said aperture, of a resilient clamping arm coöperating with said shoulder to prevent the stay-cord from backward movement.

30 6. In a buttonhole sewing machine of the type having a rotary turret carrying the under thread mechanism, the combination with a throat-plate carried by said turret and provided with an aperture through which the stay-cord is led to the work and also with a clamping shoulder adjacent said aperture, of a resilient clamping arm carried by said throat-plate and coöperating with said shoulder to prevent backward movement of the stay-cord.

35 7. In a buttonhole sewing machine of the type having a rotary turret carrying the under thread mechanism, the combination with a throat-plate provided with a stem, of means connecting the stem of said throat-plate to the turret, said throat-plate having an aperture through which the stay-cord is led to the work, and also having a clamping shoulder adjacent said aperture, and a resilient clamping arm carried by said stem and coöperating with said shoulder to prevent backward movement of the stay cord.

In testimony whereof, I have signed my name to this specification.

JOHN KIEWICZ.
